UNITED STATES PATENT OFFICE.

GEORGE WESTINGHOUSE, JR., OF PITTSBURG, PENNSYLVANIA.

ELECTRIC FLUID-PRESSURE ENGINE.

SPECIFICATION forming part of Letters Patent No. 393,596, dated November 27, 1888.

Application filed July 30, 1888. Serial No. 281,404. (No model.)

To all whom it may concern:

Be it known that I, GEORGE WESTINGHOUSE, Jr., a citizen of the United States, residing at Pittsburg, in the county of Allegheny and State of Pennsylvania, have invented or discovered certain new and useful Improvements in Electric Fluid-Pressure Engines, of which improvement the following is a specification.

In Letters Patent No. 358,520, granted March 1, 1887, is described and claimed an electrically-controlled fluid-pressure mechanism for the purpose of applying power at one, two, or more points at a distance from the operator's stand, and also to cut off, reverse, and reapply such power, as circumstances may require. The invention included in said Letters Patent, generally stated, consists in an engine wherein the controlling-valve is actuated by the same fluid-pressure which actuates the engine, said valve being controlled by electrically-actuated escape-valves.

The invention herein relates to mechanism for locking said valve in its different positions, the locking mechanism being actuated by the same fluid-pressure which actuates the valve and engine and controlled by an electrically-actuated escape-valve.

In the accompanying drawing, forming a part of this specification, is illustrated in sectional elevation a valve mechanism and its electrically-controlled locking mechanism.

In the Letters Patent above referred to the valve mechanism is described and shown as attached to the engine-cylinder; but in the present instance the valve-case 2 is formed on or secured to the auxiliary reservoir 1, the supply-ports 3 and 4 being connected to the engine-cylinder (not shown) by pipes 5 and 6. The auxiliary reservoir is connected by the pipe 7 with any suitable source of supply and with the valve-case by a passage or pipe, 8, shown in dotted lines. Between the ports 3 and 4 is formed the port 9 for the escape of fluid-pressure from one or the other of the ports 3 or 4 and their connections in accordance with the position of the valve 10, of any suitable construction, which also regulates the admission of fluid-pressure into the ports 3 and 4. Within the valve-case is arranged a double-ended piston consisting of the heads 11 11^a, connected by the hollow stem 12, hav-

ing a recessed block or U-shaped fork, 13, formed thereon for engagement with the valve 10. A small port, 14, in the stem 12 permits of an equalization of pressure inside and outside of the hollow stem. The piston-heads 11 11^a are packed in any suitable manner so that leakage past them may be small, or they may be tightly packed and a small leakage-groove (indicated by heavy black lines) may be formed in the walls of the valve-case, or other suitable means may be employed whereby fluid-pressure may flow from between the piston-heads to the spaces between said heads and the ends of the case in sufficient amount to move the heads in either direction when the pressure in the opposite end is relieved.

In the ends of the case or chest 2, and in line with the axis of the hollow stem 12, are formed valve-chambers for the reception of valves 15 15^a, which seat outwardly with the pressure. These valve-chambers are connected with the open air by escape-ports 16 16^a, the seats for the valves 15 15^a being arranged between the ports and said chambers.

Rods 17 17^a, arranged within the hollow stem 12, bear at their outer ends against the valves 15 15^a, suitable springs, 18 18^a, being arranged between the end collars on said rods and the bottoms of recesses formed in the piston-heads. These springs are preferably made of such length and are so arranged as to be operative in seating the valves only as the pistons approach the limits of their strokes. The springs are aided in seating the valves by fluid-pressure acting through the port 14 on the inner ends of the rods 17 17^a. The valves are unseated by the thrust-rods 19 19^a, each abutting against a screw-stem, 20, connected to a cap, 21, which constitutes the armature of a helix 90 or coil, 22, at each end of the valve case or chest, said coils being inclosed within the hollow annular core-extension 23.

The construction so far described is substantially similar to that described and claimed in the Letters Patent above referred to, in which the operation of said mechanism is also fully described.

It sometimes occurs in the use of the apparatus above described that the valves 15 15^a are either prevented from being fully seated by dirt or otherwise or are accidentally opened

by lightning striking the electric conductors, thereby permitting of such an escape of fluid-pressure as will disturb the equilibrium of pressure at the ends of the piston as will shift 5 said piston and with it the valve, thereby actuating the engine. In case the engine thus accidentally shifted is connected to switch-points it will be readily understood that such movement might occur just before or during 10 the passage of a train over the points would cause a derailment of the train. In order to prevent such accidental shifting of the valve mechanism I provide a locking mechanism constructed substantially as follows: On the 15 valve case or chest is formed or secured a cylinder, 24, in which is arranged a piston, 25, carrying a pin, 26, adapted when the piston is depressed or moved toward the valve case or chest to engage holes 27, 27^a in a block, 28, 20 formed on the valve-stem 12. The cylinder 24 is connected with the valve-chest, so as to permit of the flow of fluid-pressure into the cylinder by a port, 29, and provision is made, as described, in connection with the piston- 25 heads 11, 11^a for the escape of fluid-pressure past the piston 25 by a groove, 30, formed in the wall of the cylinder, or by other suitable means, for the purpose of establishing an equilibrium of pressure on opposite sides of the 30 piston, and thereby permit of the operation of the spring 21, interposed between the piston and the outer end of the cylinder, to force the piston and the pin inwardly. In a recess or chamber, 32, formed in the head of the cylinder 35 and having free communication with the interior of said cylinder, is arranged the outwardly-seating valve 33, adapted to close the passage 34, which communicates through the port 35 with the open air. The valve is seated by 40 the action of a spring, 36, surrounding the guide-rod 37 and interposed between the valve and the nut 38 in the outer end of the chamber 32. The valve 33 is unseated by a push-rod, 39, connected by the armature of a helix 45 or coil inclosed within the hollow annular core-extension 40. As the armature and helix or coil employed for operating the valve 33 are similar in construction and operation to that shown at the right-hand end of the valve, I 50 have not considered it necessary to illustrate such parts, but have shown only the case or core-extension within which they are arranged.

In the drawing, the valve 10 and its operating-connections are shown locked to the left, 55 in which position of the valve 10 fluid-pressure is admitted to the port 4 and pipe 6, leading to one end of the operating-cylinder, (not shown,) and the port 3 is connected to the exhaust-port 9, thereby allowing fluid-pressure 60 to escape from the opposite end of the operating-cylinder. If now it is desired to shift the valve 10, the circuit is completed through the helix controlling the valve 33, thereby unseating said valve and allowing the fluid-pressure 65 above the piston 25 to escape. The fluid-pressure on the under side of the piston 25

will raise it, compressing the spring 31 and withdrawing the pin 26 from the hole 27 in the block on the valve-stem 12. As soon as the above-described unlocking operation has 70 been effected the circuit through the helix 22 is completed, thereby unseating the valve 15 and permitting the fluid-pressure between the head 11 and the end of the case or chest to escape, whereupon the pressure on the opposite side of said head will shift the double-ended piston and with it the valve 10 to the right. The circuits through the helices 22 and that controlling the valve 33 are broken, thereby permitting the valve 15 and 33 to be 80 seated. As soon as the valve 33 opens the fluid-pressure escaping past the piston 25 through the groove 30 will soon establish such an equilibrium of pressure on opposite sides of said piston as to permit the spring 31 to 85 force the piston down, the pin 26 entering the hole 27 in the block on the valve-stem 12, and thus locking said stem and the parts connected therewith or operated thereby from any movement. 90

If while the above-described devices are in the positions shown in the drawing the conductors leading to the helix 22 should be struck by lightning, or a current otherwise established in such circuit, thereby opening the valve 15, 95 no shifting of the valve can be effected, as the pin 26 is in engagement with the valve-stem; and, further, in case the valve 15 should be displaced in any way, or should be prevented from being properly seated when last used, 100 the leakage past such partially-opened valve cannot effect any change of position in the mechanism as long as the pin 26 remains in engagement with the block 13. 105

Changes of structure which do not materially alter the operation or functions above described are included herein.

I claim herein as my invention—

1. In combination with the main or distributing valve of a fluid-pressure motor, a piston 110 connected therewith and operated in one direction or the other by variations in a continuously-acting fluid-pressure, an electrically-actuated valve governing the exhaust from one side of said piston, and a lock for holding 115 the distributing-valve in different positions, substantially as set forth.

2. In combination with the main distributing-valve of a fluid-pressure engine, and with a piston subject to a variable fluid-pressure in 120 opposite directions to actuate the same, magnets and valves for varying by electric agency the effective direction of the fluid-pressure on the piston, and an electrically-controlled lock for holding the distributing-valve in its different positions, substantially as set forth. 125

3. In combination with a fluid-pressure cylinder and piston, a valve governing the supply and exhaust, a piston to actuate said valve subject to fluid-pressure in opposite directions, 130 a lock for controlling the movements of said valve, escape-ports for alternately exhausting

the pressure from one side or the other of such piston, and an electrically-actuated valve to each escape port, substantially as set forth.

4. In combination with the main distributing-valve of a fluid-pressure engine, a piston subject to a variable fluid-pressure in opposite directions to actuate the same, magnets and valves for varying by electric agency the effective direction of the fluid-pressure on the valve-piston, a piston carrying a locking-pin and subject to variable fluid-pressure, a magnet, and a valve for varying by electric agency the fluid-pressure on one side of said piston, substantially as set forth.

15 5. In combination with the main or distributing valve of a fluid-pressure motor, a piston connected therewith and operated in

one direction or the other by variations in a continually-acting fluid-pressure, a piston carrying a locking-pin and subject to variable 20 fluid-pressure, an electrically-actuated valve controlling the exhaust from one side of said piston for shifting the same in one direction, a spring for shifting the piston in the opposite direction, and an electrically-actuated valve 25 governing the exhaust of fluid-pressure from one side of said piston, substantially as set forth.

In testimony whereof I have hereunto set my hand.
